J. C. D. WEEKS,
SMOKE FLUE AND CHIMNEY LINING,
APPLICATION FILED SEPT. 15, 1917.

1,278,263.

Patented Sept. 10, 1918.

UNITED STATES PATENT OFFICE.

JAMES C. D. WEEKS, OF CHEAPSIDE, VIRGINIA.

SMOKE-FLUE AND CHIMNEY LINING.

1,278,263.

Specification of Letters Patent. Patented Sept. 10, 1918.

Application filed September 15, 1917. Serial No. 191,584.

To all whom it may concern:

Be it known that I, JAMES C. D. WEEKS, a citizen of the United States, residing at Cheapside, in the county of Northampton 5 and State of Virginia, have invented new and useful Improvements in Smoke-Flues and Chimney Linings, of which the following is a specification.

This invention relates to masonry smoke flues and chimneys, and its object is to provide the same with a novel and improved shield to guard against fires from flames or sparks finding their way through cracks or crevices opening through the chimney or 15 flue from the interior thereof to the outside and exposing the surrounding partitions or other building elements to the flames, sparks or intense heat escaping through such cracks or crevices from the interior of the flue.

20 The invention also has for its object to provide a shield of the kind stated which is of simple construction, and can be readily put up, and which is securely held in place.

The objects stated are attained by means of 25 a novel combination and arrangement of parts to be hereinafter described and claimed, and in order that the same may be better understood, reference is had to the accompanying drawing forming a part of this 30 specification.

In the drawing,

Figure 1 is an elevation partly in section, showing the application of the invention;

Fig. 2 is a horizontal section of the line 35 2-2 of Fig. 1;

Fig. 3 is a perspective view showing a fragment of the lining, and

Fig. 4 is a perspective view showing the base member of the lining.

40 Referring specifically to the drawing 5 denotes a masonry chimney or flue having a central flame and smoke passage 6, with side openings 7 leading therefrom to receive the pipes or flues from the various stoves 45 in the different rooms on the several floors of the building. The floors of the building are shown at 8, and the roof at 9.

In the passage 6 is mounted a shield or lining of metal to prevent the escape of 50 flames or sparks through cracks or other defects in the brickwork. This lining is made up of a plurality of rectangular casings 10 open at the top and bottom and assembled

in superposed relation, one on the top of the other so as to form a continuous flue extending from the bottom to the top of the passage and lining the same. Certain ones of these casings are provided on one side with laterally projecting thimbles 11 extending into the side openings 7 for attachment of 60 the stove pipes or flues.

On opposite sides of each casing 10 are fastened guide straps 12 for retaining members, whereby the casings are centered and held in place in the passage 6. Each of these 65 members comprises a bar 13 having a lateral bend 14 at one end. The bar 13 forms the shank of the retaining member and seats beneath the guide 12, whereas the bend 14 extends into the wall of the flue 5 and is 70 bricked up. The bar 13 depends from the bottom of the casing 10 a sufficient distance to lap the next casing below, and the several casings are therefore securely held in alignment. As the retaining members are adjustable lengthwise in the guides 12, they 75 can be set to bring the bends 14 into any mortar joint at the side of the casing.

The bottom casing 10 has outstanding base flanges 15 which are bricked up in the same 80 manner as the retaining members hereinbefore described.

The shield affords complete protection 85 against fires from a defective flue, and it can be readily applied when the flue is being built.

I claim:—

The combination with a chimney or flue; of a lining therefor composed of a series of casings assembled in the flue in superposed 90 relation, and retaining members for the casings composed of angular bars consisting each of a shank and a laterally outwardly extending part, said members being mounted on the sides of the casings and the shanks 95 thereof depending therefrom across the joint between the same and the next casing, and the outwardly extending parts of the members being embedded in the wall of the flue, and guides mounted on the outer faces 100 of the casings in which the shanks of the retaining members are longitudinally adjustable.

In testimony whereof I affix my signature.

JAMES C. D. WEEKS.
